UNITED STATES PATENT OFFICE.

DANIEL J. MURNANE, OF TUXEDO, MISSOURI, ASSIGNOR TO THE NATIONAL MERCURY MIRROR COMPANY, OF ST. LOUIS, MISSOURI.

TABLE FOR MANUFACTURING MERCURY-BACK MIRRORS.

SPECIFICATION forming part of Letters Patent No. 650,857, dated June 5, 1900.

Application filed November 23, 1898. Renewed August 14, 1899. Serial No. 727,220. (No model.)

To all whom it may concern:

Be it known that I, DANIEL J. MURNANE, a citizen of the United States, residing at Tuxedo, in the county of St. Louis and State of Missouri, have invented certain new and useful Improvements in Tables for Manufacturing Mercury-Back Mirrors, of which the following is a full, clear, and exact description, reference being had to the accompanying drawings, forming a part hereof.

My invention relates to improvements in tables for manufacturing mercury-back mirrors; and it consists in the novel combination and arrangement of parts, as will be herein-after particularly described, and pointed out in the claims.

In the drawings, Figure 1 is a side elevation of my complete invention. Fig. 2 is a top plan view of the same, partially broken away; and Fig. 3 is a detail side elevation, with parts broken away, showing a modification of my invention.

The object of my invention is to construct a table in such manner that the glass which forms the mirror may be securely and uniformly pressed and held in position upon the upper surface or bed of the table after the said glass has been properly floated upon the mercury covering the tin-foil, thereby dispensing with the inconvenient hand-weights ordinarily employed and laid upon the upper surface of the glass for pressing or removing all the surplus mercury from between the tin-foil and glass.

A further and very important feature in connection with the clamps above referred to is the employment of a pivoted table, the bed or body portion of which is adapted to be turned bottom side up, together with the glass clamped thereon, thereby placing the mirror in a position to be easily and conveniently removed and placed upon a table or car, (not shown,) together with the clamps.

It is further to be noted that by the employment of the clamps the table can be inclined to a suitable angle, whereby the mercury located between the tin-foil and glass, after the latter has been floated to form a mirror, is almost immediately forced and drained out, and consequently the tin-foil be-

comes dry in a comparatively-short length of time, and therefore it is not necessary for the mirror to remain upon and be pressed against the upper surface of the table for many hours, as is required by the use of the hand-weights formerly employed.

It will therefore be seen that mercury-back mirrors made according to my invention can be made in a comparatively-short length of time, which is impossible under the old method, and, further, the tables can be constantly used for making mirrors and not remain idle for the purpose of drying the tin-foil, which is absolutely necessary under the old procedure before the mirror can be taken or removed from the table. Otherwise the said mirror will become damaged.

Referring to the drawings, 1 represents the bed or body portion of the table, upon the upper surface of which the tin-foil is placed over which the mercury is poured and the glass floated upon said mercury to form a mirror. Projecting from the opposite sides of the table 1 and located substantially midway between the opposite ends of the same are two trunnions 2, which are received by the bearings 3, forming the upper ends of the vertical standards 4, the bases of which are secured in any mechanical manner to the floor of the building. It is to be noted in this connection that the standards are of sufficient height to permit the bed of the table to be completely turned, as shown in dotted lines, Fig. 1, for the purpose previously stated.

The clamping device which I employ in carrying out my invention is composed of two parallel strips or pieces 5, secured together along their length by bolts 6, passing through said strips and blocks 7, which separate the strips a suitable distance. The strips are somewhat longer than the width of the table, and removably located between the same are the upper ends of two clamps 8, the heads 9 of which normally rest upon the upper edges of the said strips. The lower ends of the clamps 8 are provided with right-angular extensions 10, through which screw-threaded hand-clamps 11 pass, the upper ends of which are brought in contact with the under surface of the table 1, whereby the strips 100

are firmly brought in contact with the upper surface of the glass for the purpose before stated.

In Fig. 3 I have shown a modification of my invention, which construction is desirable for clamping glass of large dimensions in order to thoroughly press the same at intervals along its length and breadth. In this construction the clamping-screws are dispensed with, in connection with the clamps or hook-shaped connecting-pieces 8, the screw-threaded hand-clamps 11 being carried by the strips 5, the lower ends of which are brought in contact with the upper surface of the mirror and right-angular extensions of the connecting-pieces engaging with the under surface of the table.

It is further to be noted that in order to remove the mirror from the ordinary mercury-table it is necessary to first remove the hand-weights and then pry one edge of the mirror upward in order to obtain a hold to raise the same from the table, in which instance it is very easy to destroy the mirror; but by the employment of the pivoted table the mirror is gradually dropped from the table, together with the clamps, after the same are loosened, and it is therefore impossible to deface or destroy the mirror. Further, by the employment of the pivoted table it is impossible for any surplus mercury remaining between the glass and tin-foil to frost or damage the mirror in removing the latter from the table, as often occurs under the old method; but, on the contrary, the table, together with the mirror, can be so quickly reversed that there is no possible danger of injuring the mirror.

Secured to the edges of the bed 1 of the table is a trough 15, which is adapted to receive the surplus mercury which flows from the table during the process of making a mirror before the table is inverted, which is absolutely necessary in carrying out my invention and which mercury must be collected before the mirror is inverted and removed from the table; but I do not limit myself to the employment of a trough, as any suitable receptacles may be employed for receiving the excess mercury, whereby it may be collected for further use.

Having fully described my invention, what I claim, and desire to secure by Letters Patent, is—

1. A table for manufacturing mercury-back mirrors, comprising a reversible bed, a receptacle around the edge of the latter for receiving the excess mercury before the bed is inverted, and securing means comprising bars and clamps operating with said bars and ta-

ble, whereby the bed is adapted to be inverted with the mirror secured in position thereon, and whereby the mirror may be released for removal from the bed when the latter has been inverted, substantially as described. 65

2. In combination with a pivoted mercury-table, of securing means comprising parallel bars or strips secured together but separated from one another, clamps, heads forming the upper ends of the same and adapted to coöperate with the upper edges of said bars, and binding-screws carried by the clamps and adapted to be brought into contact with the under surface of the bed of the table as and 75 for the purpose described.

3. A table for manufacturing mercury-back mirrors, comprising a reversible bed, a receptacle located in a suitable position for receiving the excess mercury from the bed before 80 the latter is inverted, and means for holding a mirror in position against the upper surface of said bed, whereby the latter is adapted to be inverted with the mirror secured in position thereon, and whereby the mirror may be 85 released for removal from the bed when the latter has been inverted, substantially as described.

4. A table for manufacturing mercury-back mirrors, comprising a reversible bed, means 90 around the edge of the bed for receiving the excess mercury before the bed is inverted, and means for holding a mirror in position against the uppersurface of said bed, whereby the latter is adapted to be inverted with the 95 mirror secured in position thereon, and whereby the mirror may be released for removal from the bed when the latter has been inverted, substantially as described.

5. A table for manufacturing mercury back 100 mirrors, comprising a bed, suitable standards, means for pivotally connecting said bed to the standards about its medial portion, whereby the bed is adapted to be inverted, a receptacle for receiving the excess mercury before the 105 bed is inverted, and clamps for holding a mirror in position against the upper surface of said bed, whereby the latter is adapted to be inverted with the mirror secured in position thereon, and whereby the mirror may 110 be released for removal from the bed when the latter has been inverted, substantially as described.

In testimony whereof I affix my signature in presence of two witnesses.

DANIEL J. MURNANE.
